UNITED STATES PATENT OFFICE

EARL C. BOOTH, OF COLUMBUS, INDIANA

DESIGN FOR A HEATER CASING

Application filed July 29, 1932. Serial No. 44,476. Term of patent 7 years.

To all whom it may concern:

Be it known that I, EARL C. BOOTH, a citizen of the United States, residing at Columbus, in the county of Bartholomew and State of Indiana, have invented a new, original, and ornamental Design for a Heater Casing, of which the following is a specification, reference being had to the accompany drawing, forming part thereof.

Figs. 1 and 2 are front and rear perspective

views respectively of a heater casing embodying my new design.

I claim:

The ornamental design for a heater casing, as shown.

In witness whereof, I have hereunto set my hand at Columbus, Indiana, this 22nd day of July, A. D. one thousand nine hundred and thirty-two.

EARL C. BOOTH.
